[57] CLAIM

The ornamental design for a personal security alarm with
twin light, as shown and described.

DESCRIPTION

FIG. 1 is a top plan view of a personal security alarm with
twin light showing my new design;
FIG. 2 is a front elevational view thereof;
FIG. 3 is a bottom plan view thereof;
FIG. 4 is a left side elevational view thereof;
FIG. 5 is a right side elevational view thereof;
FIG. 6 is a front, top and left side perspective view showing
strap removed thereof; and,
FIG. 7 is a front elevational view showing a part in an
alternative position thereof.
